Bowman & Slyter,

Fountain.

No. 91,707.

Patented June 22, 1869.

United States Patent Office.

C. F. BOWMAN AND STEPHEN SLYKER, OF WILKESBARRE, PENNSYLVANIA.

Letters Patent No. 91,707, dated June 22, 1869.

IMPROVEMENT IN PNEUMATIC DEVICES FOR FORCING LIQUIDS.

The Schedule referred to in these Letters Patent and making part of the same.

To all whom it may concern:

Be it known that we, C. F. BOWMAN and STEPHEN SLYKER, of Wilkesbarre, in the county of Luzerne, and State of Pennsylvania, have invented a new and valuable Improvement in Devices for Pumping Liquids; and we do hereby declare that the following is a full, clear, and exact description of the construction and operation of the same, reference being had to the annexed drawings, making a part of this specification, and to the letters and figures of reference marked thereon.

Figure 1, of the drawings, is a front sectional view of our device.

Figure 2 is an end view of the same.

Our invention relates to means for pumping liquids; and

It consists mainly in a novel arrangement of devices, whereby liquids of many varieties may be forced to any desirable altitude at one and the same time.

The letter A, of the drawings, represents an aerometer, which we adjust in a suitable water-reservoir, in the same manner that gas-holders are arranged.

The letter B is also an air-holder, and through which air may be pumped into the aerometer A.

The letter C is a pipe, connecting the air-holders A and B with a faucet, a, operating therein.

The letter e is a faucet, or valve, for the escape of water from the chamber B.

The letter e is an air-valve, or tube, opened and closed by a faucet, through which air may be introduced to the-holders A and B.

The letter h is a pipe, connected with the holder B, through a faucet, as shown. This pipe passes over the

vessels containing the liquids, which are marked K, and small pipes, s, lead from the same into each of such vessels, in the manner represented on fig. 1.

The letters v are conduits, leading from the vessels in which the liquids are stored, and which are opened or closed by suitable faucets.

The pipe leading from the holder A to the holder B should be of elastic material, to enable the holder A to move up or down in the water.

Our device does not necessarily include the holder B, as a pipe leading directly from the holder A to the liquid-receptacles may be arranged so as to perform effective service.

To operate our device, the holder A must be filled with air, its bottom being open, and sitting in the water. Weight is then placed on the holder A, and the air is forced through the chamber B into the liquid-receptacles. This process serves to force the liquid from said receptacles through the conduits v, whenever the faucets therein are opened.

What we claim as our invention, and desire to secure by Letters Patent, is—

The aerometer A, in combination with the chamber B, air-valve e, escape e, tubes C, h, and s, constructed and operating substantially as described.

In testimony that we claim the above, we have hereunto subscribed our names, in presence of two witnesses.

C. F. BOWMAN.
STEPHEN SLYKER.
